UNITED STATES PATENT OFFICE.

WILLIAM GRINNELL LANDON, OF NEW YORK, N. Y.

CONTROL

1,383,825.

Specification of Letters Patent.

Patented July 5, 1921.

Application filed May 5, 1920. Serial No. 379,080.

To all whom it may concern:

Be it known that I, WILLIAM GRINNELL LANDON, a citizen of the United States, and a resident of the city of New York, borough of Manhattan, in the county and State of New York, have invented a new and improved Control, of which the following is a full, clear, and exact description.

It is well understood, in connection with flying machines of both the "heavier" and "lighter-than-air" type that two systems of control are utilized. These two systems are commonly called "single" and "dual" controls.

15 The first of these systems, as is apparent from the name, includes a single set of controlling levers applied adjacent the seat or cock-pit in which the operator of the machine is situated, the second including two 20 separate sets of control levers operating a single set of ailerons, elevators and rudder. This latter type is constructed for two reasons, primarily that of teaching the student operator, in which operation the instructor sits in one of the cock-pits of the 25 fuselage, the student in the second, the instructor bringing the machine off the ground, and then permitting the student operator to operate the controls while in the air.

30 The second use to which this type of machine is put being that of permitting the operation of the controls by either of the occupants of a machine, in the event that the pilot should become incapacitated.

35 It is now well understood, that any number of fatal accidents have occurred in both of these types of controls due to the fact that a control couple has often slipped from a guiding pulley, causing a jamming of the 40 elevators or other controls, resulting in a spiral or tail spin inevitably terminating in a crash.

In the event of the controls of a "lighter-than-air" machine becoming jammed, it is 45 of course possible to control the rising and landing of the machine, by shifting the weight, but it is well appreciated that this is at best a haphazard solution to the problem, which most often results in a faulty 50 landing, and a consequent destruction of the machine and injury to the occupants.

Having these defects in mind, I have conceived of a control which is equally applicable to "lighter" and "heavier-than-air" machines, and in this latter class, may be applied with ease to any desired type of plane.

Reference is had to the attached sheet of drawings as illustrating practical embodiments of my invention, and in which drawings,

60 Figure 1 is a side view of any desired type of plane, such as for instance the Curtiss J. N. 4.

Fig. 2 is a plan view thereof.

Fig. 3 is an elevational view.

Figs. 4, 5 and 6 show details of joy-stick controls which may conveniently be employed in connection with my invention, and

70 Figs. 7 and 8 illustrate a slightly modified type of tail, to which my invention may be applied, such as for instance, that of the British Handley Page machine.

In these views like reference numerals designate similar parts, and the reference numeral 10 indicates the wings of a plane, 75 11 the fuselage and 12 the landing gear, all of any desired type.

80 In the usual manner, ailerons 13 and 14 are associated with the upper and lower wings respectively of a machine, but contrary to the conventional construction separate control wires 15 have their ends connected to the ailerons their opposite ends being secured to independent joy sticks 16 and 17 respectively.

85 The usual construction may also be conveniently departed from, in that the elevators associated with the rear end of the fuselage are each split to form two pairs of flaps each arranged to one side of the rudder. These pairs of flaps, as has been illustrated 90 are designated by the reference numerals 18 and 19, the inner and outer flaps respectively being secured together, if this is desired, as has been illustrated.

95 It will also be noted that the control wires 20 and 21 respectively, control the separate pairs of elevator flaps, the wires 21 being conveniently associated with the stick 17, while the wires 20 have their ends preferably fixed to the stick 16 for a purpose hereinafter more fully specified.

100 With regard to the rudder, it will be seen that I have conveniently constructed the same in two sections 22, and 23, each of which by means of wires 24 and 25 are attached to the rudder foot bars 26 and 27 respectively.

110 Referring now more particularly to the Handley Page type of tail illustrated in Figs. 7 and 8, it will be seen that the elevator flaps 28 and 29 are each controlled by

means of wires 30 and 31, the forward ends of which are attached to the sticks 16 and 17 respectively, so that an independent control for each pair of flaps is provided.

5 It will be appreciated that this invention might be illustrated as applied to innumerable types of airplanes, and flying machines, but it is thought that the examples noted in the aforescribed drawings are of sufficient

10 clearness to illustrate the construction as applied to certain types of planes.

It will now be understood that it might not prove desirable to provide sufficiently large ailerons, elevator, flaps and rudder portions to permit of the absolute control 15 of a machine by operating one set of these controls while the second set remain inoperative and with this in view I have illustrated a convenient form of coupling whereby the motion of the sticks 16 and 17 may be synchronized.

Referring now more particularly to Figs. 4 and 5 it will be seen that this coupling may conveniently take the form of a sliding 20 clutch collar 32 by means of which a rocking of one stick will result in the rocking of the second stick, a link 33 being also conveniently interposed and having the ends attached to each of the sticks 16 and 17 to insure the transmission of motion from one 25 stick to the other in the event that the sticks are rocked longitudinal of the body.

It will be appreciated that an operator 30 may absolutely control the operation of the machine by coupling any convenient type of hand grip 34 provided with any desirable quick detachable lock 35, to the stick stubs 16 or 17 and operate the plane from either of the same. Now in the event of one of 35 the set of controls becoming jammed, the

hand grip 34 may quickly be slipped upon the opposite stick and the measure of control afforded by the second set of ailerons, elevators and rudders will permit the plane to be righted. This will be true even al- 45 though one set of controls is operating in opposition to the controls now brought into action, and it will be appreciated that a crash may be averted.

Where the sticks are coupled together in 50 the manner indicated in Figs. 4 and 5, it will be understood in the event that a jamming results, that the link and clutch may quickly be uncoupled, and a movement of either of the sticks 16 and 17 will quickly 55 indicate which set of controls is jammed, it being only necessary to couple the hand grip upon the control moving stick to permit a control of the plane.

This, as will be appreciated, is also true 60 of the foot bars 26 and 27, which control different portions of the rudder by either of which a yawing of the plane may be accomplished.

Obviously as aforesaid, my invention 65 may be applied to any number of different types of controls for different types of machines without departing from the scope of my claim.

What I claim as new and desire to secure 70 by Letters Patent is as follows:—

A control, including in combination with a fuselage, and duplicate sets of controls associated therewith, each set comprising a rudder, elevators and ailerons, of two independent joy-sticks in said fuselage, and means extending between said joy sticks for detachably connecting and synchronizing the movement thereof.

WILLIAM GRINNELL LANDON.
